UNITED STATES PATENT OFFICE.

HARVEY C. ERDMAN, OF SHAKER HEIGHTS, OHIO, ASSIGNOR TO THE NATIONAL SCREW AND MANUFACTURING COMPANY, OF CLEVELAND, OHIO, A CORPORATION OF OHIO.

METAL-WORKING MACHINE.

Application filed November 19, 1925. Serial No. 69,987.

This invention relates to metal working machines, and particularly to a machine for facing and castle turning, or facing and crowning and drilling nut blanks.

5 The principal object of the invention is to perform the necessary operations more economically, and especially to reduce the drilling time so that the cost of machining a blank, and therefore the cost of completing 10 the finished product will be reduced very materially.

In carrying out the invention, and in the attainment of the above objects, I provide a machine which operates on both ends of the 15 blank, and which prior to the drilling operations countersinks both ends of the blank so as to reduce the amount of material to be drilled, and also the drilling time, the drilling operation heretofore requiring the most 20 time of the several operations.

By countersinking both ends of the blank, not only is the drilling time reduced, but there is eliminated the necessity of subsequently countersinking the bore to remove 25 bur.

In practice the blanks are fed from a hopper and operated on successively by a series of tools, and in the preferred construction the blank delivered from the hopper 30 first passes into a chuck, and is then given the first countersinking and facing operation by a tool which operates on the forward end of the blank. Then the blank is delivered by a carrier or transfer arm into a 35 chuck carried by a turret which has a series of similar chucks into which the blanks are fed, one at a time, from the carrier. Opposite the turret the machine is provided with slidable and rotatable tools, circularly 40 arranged to correspond to the arrangement of the chucks of the turret, and corresponding in number to the number of operations to be performed on the opposite ends of the blanks. As the turret is indexed, a blank 45 is gradually carried from the receiving station through the cycle, and after being operated on by the different slidable and rotatable tools is ejected from the turret chuck.

The invention may be further briefly 50 summarized as consisting in certain novel combinations and arrangements of parts, and details of construction, which will be

described in the specification and set forth in the appended claims.

In the accompanying sheets of drawings 55 wherein I have shown a construction which operates with high efficiency, Fig. 1 is a side elevation of the machine; Fig. 2 is a top plan view; Fig. 3 is an end view looking toward the head end of the machine; Fig. 4 60 is an end view looking toward the opposite end; Fig. 5 is a transverse vertical sectional view of the tool or spindle end of the machine substantially along the line 5—5 of Fig. 6; Fig. 6 is a longitudinal sectional 65 view substantially along the line 6—6 of Fig. 5; Fig. 7 is a longitudinal sectional view through the turret with the upper portion removed, the section being taken substantially along the line 7—7 of Fig. 8; 70 Fig. 8 is a transverse sectional view substantially along the line 8—8 of Fig. 7, looking in the direction indicated by the arrows, but showing by dotted lines a cam shifting lever which is on the opposite side of 75 the plane of the section; Fig. 9 is a fragmentary view partly in side elevation and partly in section, showing the mechanism utilized in the first operation performed on the blank; Fig. 10 is an enlarged sectional 80 view showing the tool which performs the first operation on the forward end of the blank; Fig. 11 is a detail sectional view substantially along the line 11—11 of Fig. 9, this view showing how the blanks are 85 adapted to be fed into the side of the chuck which receives and holds the blank for the first operation; Fig. 12 is a sectional view through the lower part of the transfer arm or carrier which carries the blank from the 90 point where the first operation is performed, over to a chuck of the turret, the transfer arm being in position to deliver a blank to the chuck which is indicated in section, as is also a guide which assists in the delivery; Fig. 13 is a face view of the turret showing the transfer arm and guide of Fig. 11; Fig. 13^a is a fragmentary view showing 95 a side view of the guide and its support; Fig. 13^b is an edge view of the transfer arm 100 shown detached; Fig. 14 shows six end views of the blank in its various stages, and shows the operations performed on the end facing the spindle or tool end of the ma-

chine; Fig. 15 shows similar views of the blank looking from the opposite side, corresponding to the turret end of the machine, and showing the operations performed on the end of the blank facing the head or turret end; Fig. 16 shows the blank in its various stages of completion, this view showing the blank in each position in section; Fig. 17 is a view similar to that shown in Fig. 11 but showing the parts on a larger scale; and Fig. 18 is a top plan view of the collet per se.

Before describing the construction of the machine, it may be well to refer to Figs. 14, 15 and 16, wherein 10 represents the blank to be operated on, and 11, 12, 13, 14 and 15 show the blank after being given the successive operations which are given at the different working stations and which are five in number. In this instance a so-called castle nut is formed, but the machine has the same utility when operating on an ordinary nut, or other similar products.

In the first operation performed on the forward end of the blank, the latter is faced off, as indicated at 11^a, and countersunk as indicated at 11^b. The countersink is preferably annular in form, or in the form of an annular depression with tapered side walls.

The four subsequent operations are all performed on the opposite end of the blank. These include first the forming of the countersink 12^a; next the turning of the castle part of the nut indicated at 13^a and also facing, indicated at 13^b; then the first drilling operation which drills a hole part way through the blank, as indicated at 14^a; and finally completing the drilling operation indicated at 15^a.

In the event that an ordinary nut is being operated on, instead of the castle portion 13^a being turned, the end of the blank will be crowned.

It will be observed that by reason of the second countersink 12^a, the first drill has less metal to cut through than would be the case if the end surface were flat. Likewise, it will be observed that by providing the first countersink 11^b, the drilled opening 15^a is completed in less time and with less travel of the drill, the latter saving being equal substantially to the depth of the countersink 11^b. Additionally the two countersinks will cause opposite ends of the drilled bore or opening 15^a to be slightly tapered or countersunk, as indicated at 15^b and 15^c, thus doing away with the necessity of separate countersinking operations to remove bur.

Referring now to the drawings, the machine includes a bed 16, which in this instance is supported on legs 16^a, in turn resting in an oil pan 16^b. Extending through, and journaled in the bed is a shaft 17, which can be driven in any suitable way, but in this instance it is provided with a pulley

17^b, adapted to be rotated by a belt. This shaft 17 is provided with all the cams which control the various movable parts of the machine.

Supported on the bed 16 at the head end 70 of the machine is a turret 18, suitably journaled in a housing 18^a on the bed, this turret being provided with a series of chucks 19, the details of which will be referred to presently. In this instance a five-station 75 turret is employed, and it is therefore provided with five chucks 19, equally spaced about the axis of the turret.

The nut blanks 10 are fed from a suitable hopper 20, which may be supported on the turret housing 18^a. The feeding mechanism in the hopper may be of usual construction, but it preferably consists of a star-wheel 21^a on a shaft journaled in the sides of the hopper and adapted to be given a step by step movement by ratchet mechanism 21^b operated by a suitable cam indicated at 21^c on shaft 17, no attempt being made to show the details of this cam, and further description of the blank feeding mechanism being omitted as this mechanism is well known in the art in a variety of slightly modified forms.

From a trough-like neck 20^a of the hopper 20 the blanks are fed through a chute 22, the lower portion of which is vertically disposed, as clearly shown in Figs. 3 and 4. From the bottom of this chute the blanks pass through the top side and into a chuck 23 Figs. 1 and 9 which holds the blank for the first operation, which is performed on the forward face or end thereof. This chuck is supported beneath the chute 22 in a bracket 23^a supported from the bed. The chuck includes a spring collet 23^b, which is adapted to be moved inward to grip the blank by a rotary member 23^c associated with a stationary member 23^d, these two members having on their adjacent faces cam lugs and recesses arranged so that when the member 23^c 110 is turned on the rear portion or body of the collet, the camming action between the members 23^c and 23^d causes the collet to grip the blank. The member 23^c is adapted to be turned back and forth so as to cause the jaws 115 of the collet to be opened and closed by a rod 23^e and levers 23^f connected to a connecting rod 23^g which is actuated by a cam 23^h on shaft 17.

Extending centrally through the collet is a pusher 24 which is moved back and forth. When it is retracted, the lowermost blank drops in front of it, and when it is moved forward it pushes the blank forwardly into the jaws of the collet so that a portion of the blank will project beyond the jaws. This pusher 24 is supported and reciprocated by a slide 25 which slides back and forth on the bed and not only actuates the pusher but moves back and forth the tools which act 130

on the blanks supported by the chucks in the turret. In this instance the pusher is supported in a boss 25^a in effect forming a part of the slide (see Fig. 1), and a spring 25^b (see Fig. 1) is arranged between the boss and a shoulder on the pusher so that the pusher may yield in case it encounters an obstruction.

Forwardly of and in line with the chuck 23, is a combined facing and countersinking tool 26, which performs the first operation on the blank, this being on the forward end of the blank. This tool 26 is secured to the end of a revolving shaft or spindle 27 which is rotatably supported and endwise movable in bearings of a bracket 27^b suitably bolted to the side of the turret housing. The shaft is moved in an endwise direction so as to carry the tool 26 up to the forward end of the blank by a shifter 27^c engaging a collar 27^d, which is fastened to the shaft 27, the shifter being rocked back and forth by a cam 27^e on shaft 17. The shaft 27 is adapted to be rotated by a belt engaging a pulley 27^f which is keyed to a sleeve 27^g normally clutched to a collar 27^h, the clutch being indicated at 27ⁱ. The collar 27^h is in turn keyed to a sleeve 27^k having two key-way slots engaged by keys 27^l fixed to the shaft 27. Obviously, when the clutch 27ⁱ is engaged, the pulley will rotate the shaft, and normally does so. The clutch is disengaged only at intervals when it is desired to change or repair the tool 26, and the operator may disengage the clutch by throwing a lever 27^m (see Fig. 2) connected to a shifter rod 27ⁿ which is supported by the bracket 27^b (see Fig. 10) and engages the sleeve 27^g carrying the pulley.

When the yoke of the shifter 27^c is rocked so as to shift the sleeve 27^g secured to shaft 27, the tool and shaft are moved forwardly toward the blank to be machined, by a direct thrust, but to avoid chattering, I place a so-called compensator between the shifter and the stationary part consisting in this instance of the bearing or bracket 27^b supporting the shaft 27, the compensator consisting of the ring or collar 27^h and a similar ring or collar 27^p, and between which are springs 27^r (see Fig. 10) and connecting bolts 27^s which allow movement between the collars 27^h and 27^p. The parts are so arranged that when the sleeve 27^g is moved by the shifter, near the end of the forward or active stroke this sleeve comes in contact with the end of sleeve 27^k carrying the sleeve 27^g, and moves the sleeve 27^k to the right, as viewed in Fig. 10, compressing the springs 27^r so that there is a cushioning action which causes the tool 26 to be held with the right degree of firmness against the blank.

When the shaft 27 and tool 26 are moved forwardly so as to face and countersink the forward end of the blank, the pusher 24 is

retracted, the forward end of the pusher moving back beyond the lower end of the chute 22, and when the facing and countersinking operations are completed by the tool 26 it and the shaft 27 are retracted. Thereupon the pusher 24 moves forwardly, pushing the next blank into the jaws of chuck 23 and causing the blank on which the tool 26 has just operated to be moved into the mouth or socket of a pivoted transfer arm 75 or carrier 28, the tool 26 and its shaft 27 meanwhile having been retracted.

The transfer arm 28 is secured to a rock shaft 28^a mounted in a bracket 28^b secured to the upper part of the turret housing 18^a (see particularly Figs. 1, 3, 4 and 13). This transfer arm 28, the function of which is to carry the blank from the chuck 23 to one of the chucks 19 of the turret 18 is swung back and forth about the axis of the rock shaft 28^a, and this is accomplished by a rod 28^c (see Figs. 1, 3 and 4) the lower end of the rod being connected to an arm 28^d on a rock shaft 28^e, supported by a bracket on the side of the bed, and having attached to it an arm 28^f connected by a connecting rod 28^g to a cam 28^h.

When the transfer arm is swung inward to its innermost position, the blank which it carries is in line with one of the chucks 19 of the turret which was previously indexed to bring the empty chuck 19 into alignment with the blank at the lower end of the transfer arm when the latter is in the position stated. When this occurs the blank is pushed from the transfer arm into the chuck 19 by a pusher 29 (see Fig. 2) slidingly supported in a bearing 29^a carried by a spindle bracket 30 secured in fixed position on the bed 10, the main function of this bracket to be described presently.

The pusher 29 is operated by an arm 29^b (see Fig. 2) on the upper end of a vertical rock shaft 29^c carrying at its lower end an arm 29^d which is rocked by a cam 29^e on shaft 17 (see Fig. 1).

It will be noted, particularly by reference to Figs. 12 and 13, that the lower part of the transfer arm which receives the blank from the chuck 23 at the lower end of the chute 22 is formed by a fixed or rigid portion and a pivoted finger 28^k normally held in the position shown in Fig. 13 by a spring 28^m, the socket or opening which receives the blank being formed in part by the finger 28^k and a bushing 28ⁿ (see Fig. 12). The purpose of providing the pivoted finger 28^k is to insure the transfer arm against injury in the event that the blank is not entirely delivered from the chuck 23 into the transfer arm, the finger 28^k yielding so as to permit the transfer arm to swing inwardly if the blank is not clear of chuck 23.

It will be noted also that the rear side of the lower portion of the transfer arm is

notched out, as best shown in Fig. 13, and that there is provided in front of the turret a pivoted but normally stationary member 28^p, held by a light spring in the position 5 shown in Fig. 13 on a bracket 28^r extending down in front of the turret. This pivoted member 28^p serves as a guide to assist in the delivery of the blank from the transfer arm to the chuck 19 of the turret. When the 10 transfer arm swings inward to delivery position, the guide 28^p extends into the rear notched portion of the transfer arm, as indicated in Fig. 12, and when the pusher 29 pushes the blank from the transfer arm into 15 the chuck 19 of the turret, the blank slides across the tapered face at the free end of the guide 28^p.

In the event that the blank is not pushed entirely from the transfer arm so that it 20 does not actually enter the chuck 19 of the turret, it will drop down out of the way when the transfer arm is retracted or moved away from the guide 28^p instead of being carried back with the transfer arm. The 25 purpose of this guide, then, is to prevent injury or jamming in the event that the blank is not properly delivered from the transfer arm to the chuck 19 of the turret.

When the blank is properly delivered into 30 the chuck 19 of the turret it projects outwardly somewhat from the chuck, and when the turret is indexed, the outwardly projecting portion of the blank slides over the tapered face at the free end of the guide, 35 the latter then swinging downwardly on its pivot to permit the blank to pass it.

It was previously stated that the turret 18 carries a series of chucks 19, in this instance 40 five in number, and that the turret is rotatably mounted in a housing 18^a supported on the bed. The chucks 19 are all of similar construction, one being indicated in section 45 in Fig. 7. It will be observed by reference to Fig. 7, that the chuck 19 is composed of a spring collet 19^a, secured to a sleeve 19^b which extends out through the rear end of the turret. Inside the collet 19^a is a stop 19^c whose inward movement is yieldingly resisted by a spring 19^a, this stop being 50 pushed inward by the blank which is shown in position in the collet in Fig. 7. The inward movement of the stop 19^c is stopped by an adjustable gauge rod 19^d, the position of which can be adjusted by an adjustable 55 screw 19^e carried by a plate 19^f supported by studs 19^g on the rear side of the turret. It will be understood that the adjusting screws 19^e for the five chucks are all mounted in the same plate 19^f. The stop 60 19^c serves also as an ejector to eject the blanks when the chuck is opened at the end of the cycle of operations as will be explained.

To cause the jaws of the clutch to grip 65 the blank, the spring collet is moved inward

as usual into contact with a tapered ring 19^h, and to move the collet inward there is provided on the rear end of each sleeve 19^b a rocking member 19ⁱ. Each member 19ⁱ is yieldingly connected to a member 19^k, arranged adjacent a fixed member 19^l, the two members 19^k and 19^l having on their adjacent faces cam lugs and indentations. It is obvious that when the member 19ⁱ is turned on the sleeve 19^b, the two members 19^k and 19^l are cammed apart so as to retract or move inward the collet 19^a. When the member 19ⁱ is rocked in the opposite direction so that the lugs on one come into registration with the indentations of the other, the collet is moved outward and the jaws open, this being accomplished by a 70 spring 19^m.

Just as soon as the blank is moved into the jaws of the chuck, the jaws are automatically closed onto the blank and locked, and this is accomplished by a rotary cam member 31, the periphery of which is partly cam shaped and partly circular, as indicated 75 in Fig. 8. This cam member 31 is fixed to a sleeve 31^a, mounted on a shaft 32 extending centrally through the turret 18. The rear end of the sleeve 31^a carries an arm 31^b, which as shown in Fig. 7, is connected to a connecting rod 31^c, shown by dotted lines in 80 Figs. 1 and 3, and adapted to be shifted by a cam 31^d on shaft 17. As soon as the blank has been pushed into the receiving chuck 19, the cam member 31 is rocked, causing the rocking member 19ⁱ associated with the chuck in receiving position to be rocked so 85 as to turn the members 19^k and 19^l relatively, thus causing the collet to be pulled inward and the jaws closed on the blank. By reference to Fig. 8, which shows the rear ends 90 of the chucks, the centrally disposed cam member 31 and the rocking members 19ⁱ, it will be seen that the latter are provided with a series of rollers 19ⁿ which are adjacent the periphery of the cam member 31 and a series 95 of outer rollers 19^p. When the cam member 31 is rocked in the manner stated to close the jaws of the chuck onto the blank, it is moved from the position shown in Fig. 8 100 in a clockwise direction so as to cause the roller 19ⁿ, which as shown, engages the cam portion, to ride up onto the peripheral portion. This rocks the rocking member 19ⁱ, as stated above, to close the jaws on the blank, and the roller remains in engagement 105 with the circular portion of the cam member throughout the rest of the cycle so that the jaws will be retained closed on the blank until the completed blank is ready to be ejected from the machine.

Referring to Fig. 8, which as before stated, shows the rear ends of the five chucks of the turret, when a chuck receives a blank, it is in the position marked A, in this figure, 110 and the chucks in positions marked B, C, D 115

and E, through which positions each chuck successively passes as the turret is indexed, are provided with blanks which are simultaneously operated on by tools to be referred to presently.

It will be seen also, by reference to this same figure, that when the cam member 31 is rotated in the manner just explained, to lock the jaws of the chuck in position A on the blank, the roller 19^a carried by the rocking member 19ⁱ associated with the chuck in position E is released from the circular portion of the cam member 31 in the same movement of the latter which caused the roller 19^a associated with the chuck in position A to ride up on the circular portion of the cam member, and therefore to cause the blank to be locked in the chuck.

It might be here stated that at or about the time that the blank is inserted in the chuck in position A, the tools which operate on the blanks in the chucks in the positions B, C, D and E are advanced and perform their several cutting operations, and during this interval the blank in the chuck in position A is locked in the chuck by the rotation of the cam member 31, and the pusher 29 is retracted. Following this, the turret is indexed, and when the chuck moves from position E to position A, the jaws of the chuck are automatically unlocked or released from the blank, and the blank is automatically ejected by the ejector 19^c, the blank then passing down through a discharge chute which is indicated at 33 in Fig. 4.

In order that the jaws may be released from the blank when a chuck is moving from position E to position A, it is necessary that the rocking member 19ⁱ associated with the chuck be rocked to its inward position, and this is accomplished by the provision of a stationary cam member 34, (see Fig. 8) which is supported in any suitable manner from the stationary part of the machine, this cam member being so positioned that when the chuck is moving from position E to position A, the outer roller 19^p engages the cam member 34, causing the rocking member 19ⁱ to be restored to its inward or former position indicated or shown in connection with the chuck in position A. It will be understood that as the different chucks successively pass from position E to position A, the outer roller 19^p of each will successively engage the cam member 34, so that when the chuck reaches position A, the jaws will be open, ready to receive a blank, and before the chuck leaves position A, the blank will be locked in the jaws by the clockwise rotation of cam member 31. It might be here stated that while the turret is being indexed, and while the jaws of the chuck moving from position E to position A are being opened through the action of cam 34 on the associated roller 19^p, the cam member 31 is

moved back by a counter-clockwise movement as the same is viewed in Fig. 8, to the position shown in that figure.

Forwardly of the turret, and directly in line with the chucks when in positions B, C, D and E, are the four tools which respectively perform the countersinking operation 12^a, the turning and facing 13^a and 13^b (or crowning), the preliminary drilling 14^a and the final drilling 15^a, which operations are performed on the ends of the blanks facing the spindle or main tool end of the machine, and all illustrated in Figs. 14 and 16.

In Fig. 2 I have shown at 35 the tool for cutting the countersink 12^a, and at 36 the tool for performing the facing and turning operations 13^a and 13^b (or the crowning operation if an ordinary nut instead of a castle nut is being machined), and in Fig. 1 I have shown at 37 the drill for performing the first or preliminary drilling operation 14^a, and at 38 the tool for performing the final drilling operation indicated at 15^a in Figs. 14, 15 and 16. All these tools are carried by rotary and endwise movable spindles 39, rotatably mounted in endwise movable but non-rotating sleeves 40, whose forward ends are slidably supported in the bracket 30, previously referred to, and whose rear ends are slidably supported in a gear case 41, mounted on the rear portion of the bed, as shown in Fig. 1.

The sleeves, and therefore the spindles, are reciprocated or moved forwardly and rearwardly by the slide 25, which has a flat rear portion 25^c, which is guided in the bed, and at the front has an upright portion provided with a series of bosses 25^d in which the sleeves 40 are fixed and are secured by adjusting and tightening nuts 25^e arranged on opposite sides of each of the bosses. It will be remembered also, that this same slide 25 has the laterally projecting bracket extension 25^a which actuates the pusher 24 utilized in moving the blank from the bottom of the chute 22 forwardly into the jaws of the chuck 23, so that it may be operated on by the tool 26.

The slide is moved back and forth so as to give the tools 35, 36, 37 and 38 cutting strokes followed by rear idle strokes, by a cam 25^f on shaft 17, this cam being engaged by a roller 25^g on the lower side of the slide, as clearly indicated in Figs. 1 and 4.

Extending centrally into the gear box 41, and suitably journaled therein is a shaft 42 which rotates the tool carrying spindles 39, the shaft being provided with tight and loose pulleys 42^a and 42^b, the loose pulley being provided so as to stop the rotation of the spindles when it is desired to repair or replace the tools carried thereby. On this shaft are two long faced gears 42^c and 42^d, located in the gear box 41. These gears engage and rotate gears 42^e and 42^f secured to

the rear ends of the tool carrying spindles 39, the faces of the driving gears 42^a and 42^d being long enough to permit the driven gears 42^b and 42^c to remain in driven engagement throughout the stroke of the spindles in each direction. The two gears 42^a and 42^d are of different diameters, as shown in Figs. 1 and 5, the smaller gear 42^a being engaged by the gear 42^c on the spindle carrying the facing and turning tool (or the crowning tool) as it is desirable that this tool be rotated slower than the countersinking and drilling tools.

As already stated, upon the retraction of the tools 35 to 38, the turret is indexed. The indexing mechanism includes a rotating arm 43 which is mounted on shaft 17 (see Fig. 3), and rotates continuously. At the free end of the arm is a roller adapted to engage in radially disposed slots 43^a of an index plate 43^b which is secured to the rear side of the turret, as best indicated in Fig. 7. On each rotation of the arm the index plate 43^b, and therefore the turret, are turned or indexed, in this instance one-fifth of a revolution.

Associated with the index plate 43^a is a locking pin 44, which is mounted for endwise movement in a bracket 44^a on the rear side of the frame 16, the locking pin being adapted to engage in notches 43^c of the index plate so as to center and properly hold the turret in each of its several operative positions. The locking pin is retracted just prior to each indexing movement by mechanism including a lever 44^b connected to a connecting rod 44^c, which is actuated by a cam 44^d on shaft 17.

To operate the machine, power is applied to the pulley 17^b, which as before stated, drives the shaft 17 carrying the several cams, and power is applied to the pulley 27^c for rotating the front facing tool 26 and also to the pulley 42^a for rotating the rear tools 35 to 38. It might be here stated that the shaft 17 is preferably in two aligned sections connected together by speed reducing gearing in a gear box 45, shown in Figs. 1 and 3, and incorporated in this gear box also, is a clutch which can be controlled by a clutch lever 46 (see Figs. 1 and 3) by which the main section of the shaft 17 carrying the cams can be disengaged from the power driven section carrying the pulley 17^b. By throwing out this clutch the machine as a whole is thrown out of action aside from the rotation of the tools.

The operation of the machine is as follows:

Assuming that the hopper is provided with a quantity of blanks, these blanks are fed down the chute 22, and the lowermost blank drops into the top side of chuck 23, which is at the front side of the machine, just forwardly and to one side of the turret, the blank being adapted to drop into the collet when the pusher 24 is retracted. The pusher

24 then moves forwardly, pushing the blank into the chuck 23, and at the same time causing the blank ahead of it to move into the transfer arm. As the blank moves into the chuck the jaws of the latter are closed, and when the transfer arm swings inwardly to deliver a blank to the chuck 19 of the turret, the rotating tool 26 is advanced, facing and countersinking the forward end of the blank, and producing the operations designated 11^a and 11^b in Figs. 15 and 16. Then the tool 26 is retracted, the transfer arm swings outwardly, and the blank is shoved into the transfer arm, which immediately swings inward, and when it arrives in front of the chuck, in position A, the pusher 29 pushes it from the transfer arm into the chuck. About the same time, the four tools 35 to 38 are advanced and perform their respective cutting operations on blanks in the turret chucks which are in the positions B, C, D and E, as indicated in Fig. 8. As already stated, by these tools the operations designated 12, 13^a—13^b, 14^a and 15^a are performed on the end of the blank facing the spindle or rear end of the machine. Then the tools 35 to 38 and the pusher 29 are retracted, the pusher 29 being retracted, however, independently of the tools, and at or about this time the cam member 31 is actuated so as to lock the blank in the chuck of position A. Then the turret is indexed, and as the chuck carrying the now completed blank passes from position E to position A, the completed blank is ejected from the chuck, the cam member 31 meanwhile turning back again to the position shown in Fig. 8.

I have already explained the advantages of countersinking opposite ends of the blank before the drilling operations, and I need not here repeat them. As far as I am aware, I am the first to produce a machine of this character wherein nut blanks or equivalent devices are countersunk, substantially as indicated, at opposite ends so as to reduce the drilling time and the distance that the drill must be moved through the metal. Therefore these features of the machine I regard as very important parts of the invention, and as far as I am aware, are entitled to be claimed broadly.

Other important features of the invention reside in the general arrangement of the tools and the associated parts whereby the operations described, or similar operations are permitted to be performed on opposite ends of the several blanks, and also in several details of various parts of the machine by which the machine as a whole operates with rapidity and effectively to permit the finished blanks to be turned out from the machine, ready for tapping, and at a low production cost.

I do not desire to be confined to the pre-

cise details or arrangements shown, nor to a machine for performing the precise cutting operations described, nor to a machine for operating on nut blanks, but aim in my 5 claims to cover all modifications and adaptations which do not involve a departure from the spirit and scope of the invention as defined in the appended claims.

Having described my invention, I claim:

10 1. A metal working machine having a plurality of tools including a pair of countersinking tools and a drilling tool, the countersinking tools being adapted to form countersinks in the blanks of greater diameter than the diameter of the bore formed 15 therein by the drilling tool and means for presenting the blanks successively to the two countersinking tools so that the blank will be countersunk at opposite ends, and 20 then to the drilling tool.

2. A metal working machine having a countersinking tool with an operative stroke in one direction and having a plurality of additional tools including a countersinking 25 tool and a drilling tool having operative strokes in the reverse direction, the countersinking tools being adapted to form countersinks in the blanks of greater diameter than the bore formed therein by the drilling 30 tool and means for presenting blanks successively before the different tools so that a blank will be countersunk at one end, then countersunk at the opposite end, and then drilled from the latter end.

35 3. A metal working machine having a plurality of facing, countersinking and drilling tools, at least one of which has an operative stroke in the reverse direction to the others, the countersinking tools being 40 adapted to form countersinks in the blanks of greater diameter than the bore formed therein by the drilling tool and means for feeding blanks and for presenting them one at a time before the different tools where- 45 by the blank will be faced and countersunk at one end, faced and countersunk at the opposite end, and then drilled through from the latter end.

4. A metal working machine comprising 50 a turret having a plurality of chucks, tools movable toward and from the turret, blank delivery means, a chuck which receives each blank before it is delivered to the turret chucks, said chuck having a fixed position at 55 one side of the turret, and a rotating tool movable on a fixed axis toward and from the last-mentioned chuck and having an operative stroke in a direction opposite to the operative strokes of the first-mentioned 60 tools.

5. A metal working machine comprising a turret having a plurality of chucks, tools movable toward and from the turret, blank delivery means, a chuck which receives each

blank before it is delivered to the turret 65 chucks, said chuck having a fixed position at one side of the turret, a rotating tool movable on a fixed axis toward and from the last-mentioned chuck and having an operative stroke in a direction opposite to the operative strokes of the first-mentioned 70 tools, and a transfer means for carrying the blanks from the last-mentioned chuck laterally into alignment with a chuck of the turret.

6. A metal working machine comprising a tool holding part, a work holding part, the latter being in the form of a chuck having a collet provided with an opening intermediate 80 its ends, and means for delivering blanks into the chuck through the opening of the collet.

7. In a machine of the character described, a tool holding part, a work holding part in the form of a chuck having a collet provided with an opening in the top thereof, and means for delivering blanks one at a time into the chuck through the top of the collet 85 rearwardly of its forward face.

8. In a metal working machine, a tool 90 holding part, a work holding part in the form of a chuck having a collet with jaws and provided with an opening intermediate its ends, means for delivering blanks one at a time into the chuck through the opening 95 of the collet rearwardly of the jaws, and means for moving the blank forwardly into the jaws.

9. In a metal working machine, a tool 100 holding part, a work holding part in the form of a chuck having a collet with jaws and provided with an opening intermediate its ends, means for delivering blanks one at a time into the chuck through the opening 105 of the collet rearwardly of the jaws, and means for moving the blank forwardly into the jaws and then forwardly out of the chuck from the front thereof.

10. In a metal working machine, a tool 110 holding part, a work holding part in the form of a chuck having a collet with jaws and provided with an opening intermediate its ends, means for delivering blanks one at a time into the chuck through the opening 115 of the collet rearwardly of the jaws, means for moving the blank forwardly into the jaws, and means for opening and closing the jaws.

11. In a machine of the character described, a tool holding part, a work holding part in the form of a chuck comprising a sleeve having jaws at the forward end thereof, and means for moving the sleeve in an endwise direction so as to close the jaws onto the work comprising a rotary cam member arranged coaxially of the sleeve.

12. In a machine of the character described, a tool holding part, a work holding

- part in the form of a chuck comprising a sleeve having jaws at the forward end thereof, means for moving the sleeve in an end-wise direction so as to close the jaws onto the work comprising a pair of adjacent cam members, and means for turning one of said cam members in one direction to close the chuck and in the opposite direction to cause the chuck to be opened.
10. 13. The method of machining blanks which comprises countersinking one end of the blank and drilling a bore through the blank from the opposite end of less diameter than the diameter of the countersink.
15. 14. The method of machining blanks which comprises countersinking the blank at one end, countersinking the blank at the opposite end and then drilling a bore through the blank of less diameter than the diameters of the countersinks.
20. 15. The method of machining blanks which comprises moving them to different stations and at the different stations, countersinking a blank at one end, countersinking it at the other end, and drilling a bore through the blank from the latter end of less diameter than the diameters of the countersinks, the said operations while performed successively upon each blank being performed simultaneously on different blanks.
25. 16. The method of machining blanks which comprises forming an annular countersunk groove in one end of the blank and drilling a bore through the blank from the opposite end having the same center as the 35 annular countersunk groove.
17. The method of machining blanks which comprises forming an annular countersunk groove in one end of the blank and drilling a bore through the blank from the 40 opposite end, the center of which is coincident with the center of the annular countersink but the diameter of which is less than the external diameter of the countersink.
45. 18. The method of machining blanks which comprises moving them to different stations and at the different stations, countersinking an annular groove in one end of the blank, countersinking the blank at its other end, and drilling a bore through the blank from the latter end, the center of which is coincident with the centers of the countersinks but the diameter is less than the external diameters of the countersinks, 50 the said operations while performed successively upon each blank being performed simultaneously on different blanks.
55. 19. The method of machining blanks which comprises forming an annular countersunk groove in one end of the blank, a countersunk hole in the other end of the blank, and drilling a bore through the blank from the latter end.
60. In testimony whereof, I hereunto affix my 65 signature.

HARVEY C. ERDMAN.
